(57) **CLAIM**

The ornamental design for a container with external recess, as shown and described.

DESCRIPTION

FIG. 1 is a right upper perspective view of a container with external recess showing my new design;

FIG. 2 is a front view thereof;

FIG. 3 is a rear view thereof, the left side and right side views being identical; and,

FIG. 4 is a top view thereof.

All dashed lines are for environmental purposes only and form no part of the claimed design. The bottom surface of the container does not contain any ornamentality.
